UNITED STATES PATENT OFFICE.

JOHN T. O'BRIEN, WELLINGTON G. SARGENT, MARTIN DOWD, AND FRANCIS A. O'BRIEN, OF GRAND RAPIDS, MICHIGAN, ASSIGNORS TO UNIVERSAL VALVE COMPANY, OF GRAND RAPIDS, MICHIGAN, A CORPORATION OF MICHIGAN.

AUTOMATIC VALVE.

1,099,196.

Specification of Letters Patent.

Patented June 9, 1914.

Application filed October 28, 1912. Serial No. 728,140.

To all whom it may concern:

Be it known that we, JOHN T. O'BRIEN,

WELLINGTON G. SARGENT, MARTIN DOWD, and FRANCIS A. O'BRIEN, citizens of the 5 United States of America, residing at Grand Rapids, in the county of Kent and State of Michigan, have invented certain new and useful Improvements in Automatic Valves; and we do hereby declare the following to

10 be a full, clear, and exact description of the invention, such as will enable others skilled in the art to which it appertains to make and use the same.

Our invention relates to improvements in 15 automatic valves and more particularly to valves adapted to be used in automatic fire sprinkler systems and similar places where it is necessary to occasionally shut off the flow of water to prevent leakage in the 20 pipes beyond the valve, but to have the valve immediately and automatically opened as soon as the leak in the pipe is stopped, and its object is to provide a simple and cheap device which will effectively 25 accomplish the above mentioned results, and to provide the same with various new and useful features as hereinafter more fully described and particularly pointed out in the claims.

30 This device is particularly adapted, as above mentioned, for automatic fire sprinkler systems consisting of a series of pipe lines on which are placed at intervals sprinkler heads which are normally held closed by 35 fusible blocks, and which will be automatically opened to emit a spray of water when heat is applied to them. It sometimes happens that these sprinklers are inadvertently opened when there is no fire, and the water 40 issuing therefrom will do considerable damage before they can be closed and repaired.

Our invention comprises a valve which is 45 adapted to be placed in either the main supply pipe or in each one of the branches, and which may be closed in case any of the 50 sprinkler heads should begin to leak and which will remain closed as long as this sprinkler is unrepaired, but which will automatically open as soon as the leak is stopped to again allow the water to flow into the system.

The device is also provided with various other novel features of construction and arrangement as will more fully appear by

reference to the accompanying drawings, in 55 which:

Figure 1 is an elevation of a valve embodying our invention shown in position in a portion of a sprinkler pipe line, and Fig. 2 is an enlarged vertical section through 60 the axis of the valve.

Like numbers refer to like parts in all of the figures.

1 represents the header or main supply pipe from which various branch lines 2 extend, and 3 shows one of the sprinkler heads which are normally closed and are spaced at intervals along the branch lines.

4 is the body of the automatic valve which is provided at each end with screw threads 65 or other pipe connection by which it is inserted in either the main supply pipe or inlet end of the branch pipes as shown.

5 is a cylinder extending laterally from the middle portion of the body of the valve 70 and preferably disposed at an angle thereto.

6 is a cylindrical extension to the cylinder 5 slightly smaller in diameter than said cylinder and having the cap 7, preferably screwed on to its outer end, said cap being 80 provided with a central opening 7a.

The body portion 4 of the valve is provided with a conical valve seat 17 arranged at right angles to the axis of the cylinders 5 and 6 and in line therewith, and a conical 85 valve 19 is provided and adapted to fit against this valve seat. This valve 19 is piston like in shape, being provided with a cylindrical wall 20 which is somewhat smaller in diameter than the inside of the 90 cylinder 5, and may be recessed within the said cylinder, a valve stem 8 being attached to the valve for the purpose of operating it.

The valve stem 8 extends axially through the cylindrical extension 6 and the cap 7 and 95 is surrounded within the cylinder 6 by a plunger 15, said plunger also extending through the opening 7a in the cap 7, and being provided with a double faced valve 14 at its inner end which is adapted to a seat 100 in one position against an annular seat 13 at the upper end of the cylinder 6 and against the cap 7 in its opposite position.

The outer end of the plunger 15 is provided with a head 9 which is supported and 105 spaced away from the end of the plunger by arms 9a. This head is provided with an axial opening through which the valve stem

8 passes, and lock nuts 11, one of which is placed upon each side of this head, are screwed upon the valve stem, and are adapted to adjustably clamp the stem to the head 5 so that a fixed relative position may be maintained between the valves 19 and 14. A conical packing nut 10 is also screwed upon the valve stem and adapted to engage the end of the plunger to prevent the escape of 10 water through the opening surrounding the valve stem. An annular groove 16 is cut into the plunger next to the valve 14 so that when the plunger is in its lower position this annular groove or reduced portion will be 15 within the opening 7^a to prevent adhesion of these two members by rust or corrosion. The balance of the plunger, however, smoothly fits the opening 7^a to prevent the escape of water during the movement of the 20 valves. A small vent 18 is provided in the valve seat 17 to permit the flow of a small quantity of water past the valve when the same is closed for purposes hereafter described, and a knob or ball 12 is provided 25 at the end of the valve stem to manually shift the valves. It is obvious that a lever or any other well known means for operating this valve may be substituted for the ball on the end of the valve stem, this being 30 no part of the invention.

The operation of the device is as follows: Assume the valve to be open, in which position the piston valve 19 will be within the cylinder 5 and the plunger 15 in lowered position with the valve 14 seated against the cap 7 to prevent the escape of water. When any one of the sprinkler heads 3 is inadvertently opened or if any other form of leak should occur in the pipe the valve may 35 be immediately closed by manually pushing upward on the knob 12 to close the valve 19 and seat the valve 14 against the ledge 13. This shuts off the main supply of water from the pipe line and prevents any damage being done by the large amount of water 40 which would escape through the leak, but at the same time admits a small quantity of water to pass through the vent 18 so that a constant dripping will occur at the leak as 45 a reminder that the same must be repaired. The water from the pressure side of the pipe will fill the cylinder 5 behind the valve 19, and as the pressure is reduced on the opposite side of the valve by the leak in the 50 pipe the valve will be kept closed by the pressure behind it. While in this position the water is prevented from escaping from the cylinder 5 by the valve 14 held closed by the valve 19. After the leak in the pipe 55 has been repaired and the escape of water therefrom has been stopped the gradual flow through the recess 18 in the valve seat will finally fill the pipe and equalize the pressure on both sides of the valve. This pressure 60 will follow back through the cylinder 5

and exert itself against the portion of the disk 14 which is exposed through the aperture in the ledge 13. This exposed area is large enough so that sufficient water pressure may be exerted against it to raise the 70 valve 19 from its seat. This will also carry the valve 14 to the lower end of the cylinder 6 and against the cap 7 preventing any escape of water from the cylinder 6. The object of the cylindrical wall 20 of the valve 75 19 is to prevent the entrance of any obstructing material into the cylinder 5 and beneath the valve 19. In case fire should occur while the leak is still unrepairs in the pipe and the valve is closed it may be manually 80 opened by simply drawing down on the valve stem.

In adjusting the relative positions of the plunger and valve 19, both of which are mounted upon and carried by the valve stem 85 8, the packing nut 10 and both locking nuts 11 are first loosened and the valve 19 is then adjusted to its seat and the plunger 15 moved inward until the valve 14 seats against the ledge 13. The lock nuts 11 are then screwed 90 tightly against the head 9 after which the packing nut is screwed into place and the valve is then adjusted and ready for operation.

What we claim is:

1. An automatic valve, comprising a body having a passage therethrough, a branch communicating with the passage, a valve adapted to close the passage and to recede wholly within the branch leaving an unobstructed passage and a secondary valve connected to and moving simultaneously with the first named valve and adapted to close the end of the branch. 95 100

2. An automatic valve, comprising a body having a passage therethrough, a branch communicating with the passage and extending laterally therefrom, a main valve to close the passage and adapted to recede within the branch, a head at the end of the branch, an annular ledge near the middle of the branch, and a secondary valve connected to and moving simultaneously with the main valve and adapted to rest against the ledge, when the main valve is closed and against the head when the valve is open. 110 115

3. An automatic valve, comprising a body having a passage therethrough, a branch extending laterally from the body and communicating with the passage therein, a valve adapted to close the passage and to recede within the branch, an extension on the branch communicating therewith and provided with a valve seat at each end and a second valve connected to and moving simultaneously with the first named valve and adapted at each end of its stroke to seat against one of the valve seats at the respective ends of the branch extension. 120 125

4. An automatic valve, comprising a body 130

having a passage therethrough, a valve seat in the passage, a branch extending laterally from the body opposite the valve seat and communicating with the passage therein, a 5 reciprocable main valve adapted to rest against the valve seat and close the passage and to recede within the branch, an extension on the branch communicating therewith and provided at each end with a valve seat, 10 a valve stem attached to the main valve and extending axially through the branch and extension thereof, and a secondary valve mounted on the valve stem within the branch extension and adapted to engage the valve 15 seats therein at the respective limits of its stroke.

5. An automatic valve, comprising a body having a passage therethrough, a branch extending laterally from the body and communicating with the passage therein, a reciprocable valve adapted to close the passage and to recede within the branch, an extension on the branch communicating with the said branch and having a valve seat at 25 each end, a valve stem attached to the main valve and extending axially through the branch and extension thereof, a plunger mounted upon the valve stem within the branch extension and projecting out of the 30 lower end thereof, and a disk on the plunger adapted to seat against the valve seats at each end of the branch extension at the respective limits of its stroke.

6. An automatic valve, comprising a body 35 having a passage therethrough, a branch extending laterally from the body and communicating with the passage therein, a reciprocable main valve adapted to close the passage and recede within the branch, an 40 extension on the branch communicating with the same and provided at each end with a valve seat, a valve stem attached to the main valve and extending axially through the branch and extension thereof, a 45 plunger surrounding the valve stem within the branch extension and projecting through the lower end of the same, a valve mounted on a plunger and adapted to seat against the valve seats at the opposite ends of the 50 branch extension at the respective limits of its stroke, a head surrounding the valve stem and supported upon arms from the lower end of the plunger and spaced apart

therefrom, lock nuts to screw upon the valve stem to adjustably clamp the same 55 to the head and a packing nut screwed upon the valve stem and adapted to engage the end of the plunger.

7. An automatic valve, comprising a body having a passage therethrough, a cylindrical branch extending laterally from the body and communicating with the passage therein, a cylindrical extension on the branch smaller in diameter than the main branch, co-axial therewith and communicating with 65 the same, a valve seat between the main branch and the extension thereof, a valve seat at the end of the branch extension, a valve stem connected to the main valve and extending axially through the branch and 70 extension thereof, a plunger surrounding the valve stem and adjustably attached thereto within the branch extension and projecting through the valve seat at the lower end of the same, a valve on the inner end 75 of the plunger adapted to alternately engage the valve seats at the opposite ends of the branch extension to close communication between the branch and extension thereof when the main valve is closed and to 80 prevent the escape of fluid from the branch extension when the main valve is open.

8. An automatic valve, comprising a body having a passage therethrough, a valve seat in the passage, a branch extending laterally 85 from the body and communicating with the inlet side of the passage, a main valve adapted to engage the valve seat to close the same and to recede into the branch when opened, a valve seat at the outer end of the branch 90 and the secondary valve connected to and moving simultaneously with the main valve and adapted to engage the valve seat at the end of the branch to close the same when the main valve is closed, and a restricted bypass connecting the inlet with the outlet 95 sides of the passage.

In testimony whereof we affix our signatures in presence of two witnesses.
